Primary Examiner — Lakiya G Rogers*Assistant Examiner* — Carissa C Fitts(74) *Attorney, Agent, or Firm* — Thomas I. Rozsa**(57) CLAIM**

The ornamental design for a magnetic flashlight, as shown and described.

DESCRIPTION

FIG. 1 is a front side perspective view of the magnetic flashlight with the top portion magnetically connected to the bottom portion, showing my new design;
FIG. 2 is a front view thereof;

FIG. 3 is a rear view thereof;

FIG. 4 is a left side view thereof;

FIG. 5 is a right side view thereof;

FIG. 6 is an exploded front view thereof with the top portion removed from the bottom portion;

FIG. 7 is a top view of the top portion thereof;

FIG. 8 is a bottom view of the top portion thereof;

FIG. 9 is a top view of the bottom portion thereof; and,

FIG. 10 is a bottom view of the bottom portion of the magnetic flashlight.

The broken lines shown in FIG. 1 are for environmental purposes only. All other broken lines show portions of the article which form no part of the claimed design.
